(57) **CLAIM**

The ornamental design for a magnetic garment restraint, as shown and described.

DESCRIPTION

FIG. 1 is a front perspective view of the magnetic garment restraint of the instant invention;

FIG. 2 is an enlarged left side view of the clasp;

FIG. 3 is a front view thereof;

FIG. 4 is right side view of the clasp;

FIG. 5 is a front view thereof;

FIG. 6 is an enlarged partial view of FIG. 4;

FIG. 7 is a bottom view; and,

FIG. 8 is a bottom view shown in its environment.

The broken line showing of a strap in FIGS. 1, 7 and 8 and clasp tabs in FIGS. 1–5 and 7–8 is included for the purposes of showing environmental portions of the magnetic garment restraint and forms no part of the claimed design.
